BOTTLE CAP

Isaac L. Wilcox, Fulton, N. Y., assignor to Oswego Falls Corporation, Fulton, N. Y., a corporation of New York

Application September 2, 1937, Serial No. 162,166

2 Claims. (Cl. 215—38)

This invention relates in general to hood or cover-all caps for bottles and the like, and more particularly to a hood cap pre-formed, or partially pre-formed, from thin, flexible material and involving a construction by which the cap will remain in pre-formed condition until applied to the bottle.

Due to the fact that bottles capped with hood caps, particularly milk bottles, are subject to extreme moisture, it is necessary that the material from which the hood cap is made be moisture-proof, or moisture repellent. Generally, these caps are made from paper which is processed or treated in some manner to render it moisture-repellent. However, this additional processing adds to the cost of the material from which the cap is formed, and is not entirely satisfactory, particularly in that moisture penetrates the cap at the points where the material is creased or folded. There are materials which are inherently moisture-proof, such as "Cellophane," but these materials possess a comparatively high degree of resiliency, and for this reason it has heretofore been thought impractical to construct hood caps in a partially pre-formed state from such material. There are instances where it is desirable to partially pre-form the cap instead of forming it from a flat blank and simultaneously applying it to the bottle. Due to the resiliency of the material, hood caps partially pre-formed have a tendency to return to flat condition.

This invention has as an object a construction and method by which hood caps may be partially pre-formed from such resilient material, and which will remain in pre-formed condition until applied to the bottle.

The invention consists in the novel features and in the combinations and constructions and the method hereinafter set forth and claimed.

In describing this invention, reference is had to the accompanying drawing in which like characters designate corresponding parts in all the views.

Figure 1 is a plan view of the blank previous to being drawn into cup form.

Figure 2 is a side elevational view of a plurality of caps arranged in nested condition, which caps have been partially pre-formed from the blank shown in Figure 1.

Figure 3 is a side elevational view of the cap applied to the top portion of the bottle.

Figure 4 is a bottom view of a cap pre-formed from the blank of Fig. 1.

At the present time, I find that "Cellophane"

is a material particularly well adapted for the formation of my cap, and I prefer to form the cap from disks 10 of this material. The marginal portion of the disk is coated, at circumferentially spaced apart points indicated at 11, 5 Figure 1, with a suitable adhesive in the nature of thermo-plastic, or like solvent. Subsequently, the marginal portion of the disk 10 is drawn or bent downwardly forming a depending outwardly flaring skirt portion 12. The central portion 10 13 of the blank constitutes the discoidal top portion of the cap. In this drawing operation, the previously coated portions 11 are folded to form subsequently overlapping pleats, and while the blank is thus folded into cup form, the upper end 15 portions 14 of the pleats are pressed together and are sealed or secured in overlapping relationship by the adhesive. At this time, the remaining portion of the pleats are in expanded form. That is, the skirt 12 is not drawn or contracted sufficiently to effect a complete overlap of the pleats. Due to the fact that the upper end portion of the pleats are sealed together, any tendency of the blank to return to flat normal condition is resisted and prevented, and the caps in this cup 20 shape form may be shipped in nested condition, as illustrated in Figure 2.

Subsequently, the caps are individually applied over the top of the bottle B, and the skirt portion 12 contracted about the neck of the bottle, and the remaining portion of the pleats pressed together and sealed in overlapping relationship, whereby the cap is securely fixed to the bottle. With certain types of adhesive, it will be necessary to apply heat during the contraction of the 35 skirt 12 in order that the pleats may be permanently sealed throughout their length.

While I have made particular reference to "Cellophane," it will be obvious that other materials of like nature may be employed in carrying out the invention.

The important feature of the invention resides in pre-forming a hood cap and maintaining the same in pre-formed condition by sealing or cementing the upper portion of the pleats together.

What I claim is:

1. A bottle cap partially preformed from thin, resilient, sheet material, said cap comprising a discoidal portion extending across the top of the bottle and a depending skirt portion of pleated formation adapted to be contracted about the neck of the bottle when the cap is applied to the same with the pleats in overlapping relationship throughout substantially their entire length, the pleats of said partially preformed cap being ar- 50

- 5 ranged in overlapping relationship throughout a portion of their length and in expanded relation throughout the remainder of their length, and said overlapping portion of the pleats being permanently secured together and maintaining the skirt in depending condition.
- 10 2. A bottle cap partially preformed from thin, resilient, sheet material, said cap comprising a discoidal portion extending across the top of the bottle and a depending skirt portion of pleated formation adapted to be contracted about the neck of the bottle when the cap is applied to the same with the pleats in overlapping relationship throughout substantially their entire length, the pleats of said partially preformed cap being arranged in overlapping relationship throughout a portion of their length and in expanded relation throughout the remainder of their length, and said overlapping portion of the pleats being permanently secured together and maintaining the skirt in depending condition, and the expanded portion of said pleats being coated with an adhesive to subsequently secure said portions together upon contraction of the skirt about the neck of the bottle. 10

ISAAC L. WILCOX.
